ABRADING OR SANDING MACHINE AND
METHOD

Norman Potash, Baltimore, Md.

Application March 15, 1938, Serial No. 196,058

6 Claims.

(Cl. 51—66)

This invention relates to a method of abrading, sandpapering or sanding, and to a machine for the same, for use in the woodworking arts. Particular objects and advantages of the invention will be hereinafter set forth.

In the accompanying drawings which represent what is at present believed to be the preferred embodiment of the invention:

Fig. 1 is a top plan view;
10 Fig. 2 is a longitudinal section on the line 2—2 of Fig. 1, with certain parts shown in elevation, and other parts omitted;

Fig. 3 is a fragmentary perspective view of one of the two table sections and part of the supporting frame;

Fig. 4 is a sectional view, on a larger scale, of part of the mechanism shown in section under the bracket 4—4 in Fig. 2;

Fig. 5 is a diagrammatical top view showing 20 the reciprocating abrading action of the machine;

Fig. 6 is a perspective detail view of parts of one of the reciprocating carriers for the sanding shoes or plates;

Fig. 7 is a perspective detail view of parts of 25 the mechanism for driving the carrier shown in Fig. 6, with a slide-block forming part of said mechanism shown cut away;

Fig. 8 is a perspective detail view of said slide-block;

Fig. 9 is a perspective detail view of a sanding shoe or plate adapted to be mounted on and to constitute part of one of the carriers, other parts of which are shown in Fig. 6;

Fig. 10 is a fragmentary detail view in elevation 30 of a modified form of rubber belt for the sanding shoes;

Fig. 11 is a vertical sectional view on line 11—11 of Fig. 10;

Fig. 12 is a vertical sectional view on the line 12—12 of Fig. 1, with some parts shown in elevation;

Fig. 13 is a detail perspective view of the driving shaft coupling;

Fig. 14 is a fragmentary view in side elevation 45 of one of the sand belt tensioning or take-up devices; and

Figs. 15 and 16 are detail perspective views of 50 an adjustable guide for material to be fed into the machine.

The supporting framework comprises a pair of tubular bars 20 and 21, supporting two tables or table sections 24 and 24'. Reinforcing ribs on the underside of the table sections have holes through which pass the bars 20 and 21. A detail of this mounting is seen in Fig. 3, wherein bar 21 passes through a hole in rib 26 of table section 24'. The bars 20 and 21 are supported between the two end frame members 22 and 23. Four 55 depending legs 29 support the assemblage. Table

24 is fixed to member 22 by screws 27 and 28. Table 24', however, is slidable on the bars 20 and 21 and may be moved thereon relative to table 24 by operation of the crank connection 30.

Fig. 2 illustrates the principal shaft and gear connections of the driving mechanism. Power from a source not shown is transmitted, as by belt 25, to pulley 31 mounted on shaft 32. Shaft 32 is journaled in bearings 33 and 34 mounted beneath table 24, and passes through suitable openings in the before mentioned ribs of said table. Shaft 32' beneath table 24' is journaled in bearings 33' and 34' for rotation on the same axis with shaft 32; and the two shafts are connected by a coupling shown in detail in Fig. 13, and comprising a tongue 36 formed on shaft 32', and the socket 37 on shaft 32.

Shaft 40 is journaled in the bearings of two supports 41 and 42 on the top of table 24 and is driven counter to shaft 32 by a pair of connecting gears 43 and 44 extending through an aperture in the table. Shaft 40' is mounted on table 24' for rotation on the same axis with shaft 40, and is similarly journaled on the bearings of supports 41' and 42' and driven counter to shaft 32' by connecting gears 43' and 44'.

Two reciprocating carriers for bands or belts having surfaces of sanding or abrasive material are driven from the shafts 40 and 40' respectively. The inner or opposing ends of said shafts 40 and 40' carry blocks 99 and 99' on which are formed the eccentric end portions or crankpins 45 and 45' which actuates the opposed reciprocating carriers respectively, as will be further described presently. The outer end of shaft 40 carries a bevel gear 46 which meshes with bevel gear 47 mounted on vertical shaft 48. The lower end of shaft 48 carries a driving sprocket 49, and from said sprocket a sprocket-chain 50 (see cut-away and dotted portions in Fig. 1) forms the driving means for all sand belt driving pulleys 40 and slat feeding rollers and rotary brushes carried by table 24. Similarly, shaft 40' on table 24' carries a bevel gear 46' at its outer end, which gear meshes with bevel gear 47' on vertical shaft 48' for operating sprocket 49'. Sprocket 49' drives the belt driving pulleys and slat feeding rollers and rotary brushes on table 24' by a chain 50', which operates on a higher plane (due to the shorter shafts employed) than chain 50 to avoid interference at the opposing edges of the two tables (see Fig. 12).

Two abrading or sanding bands or endless belts 55 and 55' having opposed portions where said bands or belts pass over the reciprocating carriers respectively and engage the interposed work 55 to be abraded, are mounted and driven on the two tables 24 and 24' respectively. Starting from the point at which it leaves the plate 70 of the left hand carrier (Figs. 1 and 5), belt 55 travels toward the left, against the take-up or tensioning 60

roller 51 and around the idler pulley 52. Four of these tensioning rollers may be seen in Fig. 1, numbered 51, 51a, 51b and 51c, supported on the axles of the idler pulleys 52, 52a, 52b, 52c. Fig. 5 14 is a detail view of tensioning roller 51c and idler pulley 52c. This idler pulley revolves on axle 53. A pair of arms 57 and 58 extending from axle 53 support the axle 56 which carries roller 51c. Spring arm 59 is fixed to the top 10 of axle 53 by a bolt 66 in Fig. 14, and bears against axle 56 forcing roller 51c against sand belt 55'. By loosening set screw 65 and turning axle 53 the pressure of the spring arm against axle 56 may be adjusted, and the flapping of the sand 15 belt due to the reciprocating movement of the right hand carrier comprising plate or shoe 70', and also any undesired slack, may be taken up. The sanding or abrading bands or belts should at all times be maintained with slack at the 20 minimum to prevent slippage of the belts on the carriers when the latter are in operation. From tensioning roller 52, the belt passes around the large driving pulleys 60 and 61 (Fig. 1). Pulley 61 and its driving connection are shown in Fig. 12, 25 wherein pulley 61 is mounted on a vertical shaft 62 in a tubular housing 64 extending through table 24. Sprocket 63 at the lower end of shaft 62 is driven by chain 50.

From pulley 61 the sanding belt 55 passes 30 around idler pulley 52a and tensioning roller 51a, and returns to and around the reciprocating carrier comprising shoe 70. The belt advances in the direction indicated by arrows in Fig. 1.

The belt 55' and its supporting and driving 35 parts are similarly arranged on table 24'. Corresponding parts bear the same reference numerals accompanied by primes. All pulleys and rollers carrying the sanding or abrading bands or belts are preferably covered with rubber facings to 40 prevent slippage.

The two reciprocating opposed carriers, comprising plates or shoes 70 and 70', over which pass the belts 55 and 55' respectively, are mounted on the opposed edges of the tables 24 and 24', as shown in Figs. 1, 2 and 4, in which corresponding parts have the same reference numerals, those on table 24' being primed. Figs. 6 through 11 are detail views of the reciprocating carrier which comprises the plate or shoe 70' and its supporting parts, the description of which may be applied to those of the corresponding left-hand reciprocating carrier which comprises the plate or shoe 70 on the table 24.

In Fig. 6, the U-shaped support 72' has a flat 55 base adapted to be bolted to table 24'. A pair of horizontally disposed parallel bars 75' and 76' are clamped in semi-circular grooves across the forward faces of the upright arms 73' and 74' by the clamping members 77' and 78' which latter are also provided with semi-circular grooves. The reciprocating frame 80' is preferably of aluminum and is slidably mounted on the bars 75' and 76' for lateral movement. Suitable bushings 81' and 82' are provided in the bar-openings of the frame 80', and oil-cups 83 and 84 lubricate bars 75' and 76' respectively. In the center of the frame 80' there is a rectangular aperture 85' having bearing plates 86 and 87 on the side walls thereof and oil-cups 88 and 89 for lubricating said plates. In Fig. 7 the block shaped counterbalance 99' is shown with the crank pin 45' formed on the upper part of its forward face, and is mounted on the end of shaft 40' by an off center boring, and secured by two screws 102' and 103'. 70 The larger and heavier portion 104' is disposed at

the opposite side of the shaft from the crank pin to counteract the centrifugal thrust of the latter. Slide block 91', shown in detail in Fig. 8, is carried by crank pin 45' and retained thereon by cap 92' screwed to the end of the pin. These 5 parts are shown in assembled position in Fig. 4. Slide-block 91' fits snugly to the bearing plates 86 and 87 on side walls of the aperture 85' and when crank pin 45' is rotated, slides in a vertical path therein while imparting to frame 80' the 10 lateral movement of the crank pin.

Fig. 9 is a perspective detail of the plate 70' constructed of sheet metal, preferably aluminum. Plate 70' has two rearwardly bent upper and lower flanges 93' and 94' adapted to fit over the top 15 and bottom respectively of frame 80', and are attached thereto by four screws two of which, 95' and 96', for the top, are shown in Fig. 9. At each vertical edge of the plate 70' are mounted the rollers 97' and 98' (preferably of aluminum) rotatable on vertical axles extending between the flanges 93' and 94'. Trained around these rollers and across the face of plate 70' is the endless belt 100', preferably of a resilient material such as 20 sponge rubber having a flexible backing 105 of 25 canvas or like material. Additional resiliency may be obtained by cutting or forming a tread in the rubber face of the belt, such as shown in the modified belt 101 of Figs. 10 and 11. The belt is movable around the rollers 97' and 98' 30 and plate 70' in the same direction with the sanding belt 55' when the machine is in operation.

In Fig. 1 a slat or board 71 is shown being fed into the machine between the two opposed sanding belts. Beginning at the lower edge of the 35 machine in said figure, the slat 71 rests against an L-shaped adjustable guide 110 mounted at the edge of table 24 (see also Figs. 15 and 16). The base of the guide is fixed to the table by a pair of screws 111 and 112 passing through slots 40 113 and 114 having sufficient length to allow lateral adjustment of the guide for different thicknesses of slats or boards. The upright portion of the guide has two vertical slots 115 and 116. A bar 117 is clamped to the face of the 45 guide by bolts 118 and 119 passing through said slots. The lower edge of slat 71 being fed through the machine, rests on bar 117, the latter having been adjusted to guide the slat at the proper height for feeding. From guide 110 the slat 50 passes between two positively driven feed rollers 118 and 118', from which point the feeding of the slat is automatic. The rollers 118 and 118' are preferably of solid rubber, and are located respectively at the edges of tables 24 and 24' in 55 the position shown in Figs. 1 and 12. In Fig. 12 the roller 118 is mounted on a vertical shaft 119 rotatable in tubular housing 120 extending through table 24. Sprocket 121 at the lower end of the shaft engages chain 59. Roller 118' is 60 similarly mounted on shaft 119' in housing 120'. Sprocket 121' is driven by chain 59'.

The slat 71 next passes between the portions 65 of sanding belts 55 and 55' which pass over the reciprocating carriers comprising shoes 70 and 70' respectively, and is sanded. In Fig. 5 the movements of the parts are diagrammatically represented. It will be noted that the carriers comprising the shoes 70 and 70' and the portions 70 of the sanding belts passing thereover reciprocate in opposite directions; when one shoe is moving in the direction of feed of the slat 71, the other is moving in the opposite direction, and vice versa. This arrangement gives the best 75 sanding results and also prevents the slat from 75

being pulled in one direction or the other and interfering with the feed. From between the shoes the slat 71 passes between a pair of rotary cleaning brushes 122 and 122' (Figs. 1 and 5) which are mounted on tables 24 and 24', and rotated opposite to the direction of travel of the slat. The supports and driving sprockets for the brushes are not shown in detail in the drawings, but correspond generally to those previously described for the feed rollers 118 and 118'. The sprockets connecting the brushes with chains 50 and 50' should, however, be smaller than those for the feed rollers, to provide comparatively greater speed of rotation in the brushing action. The brushes not only clean the slats after they are sanded, but, by reason of their location closely adjacent the shoes, also clean the sand belts as well. The belts are alternately pressed against the brushes at the end of the stroke of the shoes toward said brushes, as shown in Fig. 5. From the cleaning brushes 122, 122', slat 71 passes between positively driven feed rollers 123, 123' similar to and driven in the same manner as that previously mentioned for feed rollers 118, 118'. The chains 50 and 50' after passing around the sprockets for rollers 123, 123' pass over the idler sprockets 124 and 124' on axles depending from the tables 24 and 24' respectively. The courses of the chains are shown in dotted lines in Fig. 1, and require no added description.

The invention may be constructed to any desired proportions according to the requirements of the particular materials to be sanded. The machine shown in the drawings is especially adapted for sanding materials ranging from thick boards to very thin strips of wood, such as slats to be used in Venetian blinds.

In such a machine the following dimensions and speeds are suggested as being preferable; the length of the plates or shoes 70, 70', 8 inches; speed of sand belts 55, 55' and of slat feeding parts, 8 inches per second; number of reciprocating strokes of shoes, 40 per second; length of said strokes, 1 1/4 inches; speed of brushes 122 and 122', 40 inches per second. A machine constructed and adjusted accordingly will deliver 40 sanding strokes to every point on a slat.

As thus appears from the foregoing description, the machine is capable of sanding both sides of slats or boards simultaneously and by a very advantageous reciprocating rubbing action consisting of a large number of short, quick strokes. During this action the feeding and brushing of the slat is continuous and automatic. Long lengths of sanding belt are provided and these are continuously moved and cleaned to present a fresh sanding surface to the reciprocating shoes. The feeding, sanding, and brushing parts may be readily adjusted by a single adjusting means to materials of varying thicknesses. All moving parts are driven from a central source of power, and the speeds thereof positively coordinated without the need of separate regulation. The amount of sanding action may be increased or diminished by the aforesaid adjusting means and also by employing on the shoes sponge rubber belts of greater or less resiliency as desired. This is of particular importance for work where the board or slat has already been primed or flat-coated, and must be sanded lightly.

The method consists in continuously feeding the slat, board, or like material; in passing the

same between a pair of continuously moving opposed sanding belts; in imparting to the opposed surfaces of said belts a reciprocating sanding action independent of said movement. The method may also include brushing or cleansing said slat after it is sanded, and cleansing the belts.

What is claimed is:

1. An abrading or sanding machine including, in combination, a pair of endless abrading belts, means for supporting said belts with portions of their faces in opposed relation, means for advancing said belts, means for feeding work material between said opposed portions of the faces, and common means for simultaneously brushing said material and said belts after the sanding operation. 10

2. An abrading or sanding machine including, in combination, a pair of opposed plates or shoes, a pair of endless abrading belts trained over the opposed surfaces of said shoes, means for advancing said belts, driving means for imparting to said shoes and said belts a reciprocating abrading motion, and synchronizing means associated with said driving means for maintaining the said reciprocating abrading motion of said shoes and 20 said belts in directions opposite to each other. 25

3. An abrading or sanding machine including, in combination, supporting means, a pair of table sections mounted on said means with an edge of one section adjacent an edge of the other section, 30 a pair of opposed plates or shoes mounted on said sections near said edges respectively, a pair of endless abrading belts mounted on pulleys carried by said sections respectively and trained over the opposed faces of said shoes, feeding means comprising pairs of feed rollers, brushing means comprising a pair of rotary brushes; chain driving means for rotating said belts, said feeding, and said brushing means; and crank driving means for imparting to said shoes and said belts 35 a reciprocating abrading motion. 40

4. An abrading or sanding machine including, in combination, a pair of opposed endless abrading belts, means for supporting the same with portions of their faces in opposed relation, means 45 for advancing said belts, means for imparting to said opposed portions a reciprocatory abrading motion, means for feeding work material between said opposed portions; a pair of rotary cleaning brushes each disposed for contacting a belt and 50 a side of the material after the abrading operation, and means for driving said brushes in a direction opposite the direction of feed of the material and in a common direction with the direction of drive of the belts whereby said belts 55 are cleaned by a picking action.

5. An abrading or sanding machine according to claim 4, wherein the rotary cleaning brushes are brought into intermittent contact with the belts by the reciprocatory abrading motion of the latter. 60

6. An abrading or sanding machine including, in combination, a pair of opposed plates or shoes, a pair of endless belts trained over the opposed surfaces of said shoes, means for advancing said 65 belts, and means connecting said shoes with a single source of power for imparting to each shoe and belt a reciprocating abrading motion in a direction opposite to that of the other shoe and belt. 70
